ABSTRACT OF THE DISCLOSURE

A bifurcated tool for twisting devices supported at an elevated position is disclosed. The tool is provided with a latch means so that the tool may be automatically latched to the device to prevent undesired separation.

This invention relates to a bifurcated tool, and more particularly, to a bifurcated tool for twisting devices supported at an elevated position. An example of such a device is the cage for an electrical device mounted on the ceiling of a room. More particularly, the electric light bulbs in gymnasiums are generally provided with a cage surrounding the same to prevent the bulbs from being inadvertently broken.

The tool of the present invention includes an elongated handle. The handle may have separable components or may be of a telescoping type to facilitate reaching elevated positions. The tool is provided with a latching means such as detents whereby the cage will not separate from the tool while the tool is being moved from a vertical position to a horizontal position and vice versa.

It is an object of the present invention to provide a novel bifurcated tool for twisting devices supported at an elevated position.

It is another object of the present invention to provide a novel bifurcated tool for twisting devices supported at an elevated position.

It is another object of the present invention to provide a bifurcated tool having a latching means to prevent inadvertent separation between the tool and a device to be rotated thereby.

It is another object of the present invention to provide a novel tool for twisting devices which is simple, economical, reliable, and easy to manufacture.

Other objects will appear hereinafter.

For the purpose of illustrating the invention, there is shown in the drawings a form which is presently preferred; it being understood, however, that this invention is not limited to the precise arrangements and instrumentalities shown.

FIG. 1 is an elevation view of the tool of the present invention when being used.

FIG. 2 is a perspective view of the tool shown in FIG. 1 but on an enlarged scale and minus the handle.

FIG. 3 is an enlarged side elevation view of the tool shown in FIG. 1.

FIG. 4 is a sectional view taken along the line 4—4 in FIG. 3.

FIG. 5 is a sectional view taken along the line 5—5 in FIG. 4.

FIG. 6 is a sectional view taken along the line 6—6 in FIG. 5.

Referring to the drawing in detail, wherein like numerals indicate like elements, there is shown in FIG. 1 a tool designated generally as 10. The tool 10 includes a head 12 and a handle 14. The tool as illustrated is adapted to twist a cage 16. Cage 16 is threaded into a surrounding relationship with respect to an electric light bulb 18 threaded to a socket on ceiling 20.

The head 12 is provided with an integral hollow extension or tubular portion 22. The handle 14 is telescoped into portion 22 and removably connected thereto by means

2

of a bolt 24. One or more such bolts may be utilized as desired.

The head 12 is generally rectangular and is provided with a plurality of projections which terminate in flat end faces lying in the same plane. As illustrated, four such projections are provided, designated as 26, 28, 30 and 32. The projections are defined by intersecting slots 34 and 36 lying in mutually perpendicular planes. The slots 34 and 36 have a depth which is less than the height of the head 12.

The slots 34 and 36 are preferably made by a circular milling tool so as to define arcuate surfaces on the bottom of the grooves as shown more clearly in FIG. 5. The corner of each projection at the intersection of slots 34 and 36 is preferably beveled as illustrated more clearly in FIG. 4 by use of a drill bit.

The tool 12 is provided with a latching means. As shown, the latching means is designed to interconnect the tool and cage so as to prevent undesired separation of the same. An example of such undesired separation is when the handle 14 is being moved from a solid line position as shown in FIG. 1 to a phantom position as shown in FIG. 1. During such movement, it is undesirable to permit the cage 16 to fall freely.

The latching means as illustrated is in the form of sets of detents. As shown more clearly in FIG. 6, projection 32 has a ball detent 38 and projection 26 has an oppositely disposed ball detent 40. As shown more clearly in FIG. 4, the ball detents are aligned and extending towards each other into the slot 34. Similar ball detents 42 and 44 are provided on the projections 30 and 32 respectively.

All of the ball detents are identical. Hence, only those shown in FIG. 6 will be described in detail. Ball 38 is biased to the position shown by means of spring 48. The tension of spring 48 is controlled by rotating the threaded plug 46. Ball 40 is biased to the position shown in FIG. 6 by spring 52. The tension of spring 52 is controlled by rotating the threaded plug 50. The ball detents are at an elevation which is approximately one-half the depth of the groove 34. While only groove 34 is provided with detents, groove 36 may also be provided with detents if desired. The plugs 46 and 50 may be provided with a screwdriver slot or with an Allen wrench socket to facilitate adjusting the same as illustrated.

If desired, the interior of head 12 may be drilled to provide a passage 54. Passage 54 communicates with the hollow interior of portion 22 and the slots 34 and 36 at the intersection of said slots.

In view of the above description, a detailed recitation of operation is not deemed necessary. The cage may be manually attached to the head 12 by pushing the same inwardly until it is held by the ball detents. Thereafter, the handle 14 may be elevated to a position wherein it is desired to thread the cage 16 to a mating ring surrounding the electric light bulb 18. The tool may be utilized for rotating other devices in addition to cages.

The present invention may be embodied in other specific forms without departing from the spirit or essential attributes thereof and, accordingly, reference should be made to the appended claims, rather than to the foregoing specification as indicating the scope of the invention.

I claim:

1. A tool comprising a head having projections defined by intersecting slots extending from an end face of the head, a handle attached to the end of said head remote from said face, and ball detents on some of said projections for latching said head to a device to be rotated by said head, said ball detents projecting into at least one of said slots.

2. A tool in accordance with claim 1 wherein said slots are provided with curved bottom surfaces.

3. A tool in accordance with claim 1 wherein said head has four such projections defined by the intersection of two slots at right angles to each other, and said ball detents projecting into only one of said slots on opposite sides of the other slot.

4. A tool in accordance with claim 1 wherein said end face is flat, and said projections are generally rectangular in configuration, each projection having a beveled corner adjacent the intersection of said slots.
